UNITED STATES PATENT OFFICE

2,553,803

CARTON

Julius A. Zinn, Jr., Chicago, Ill.

Application March 25, 1947, Serial No. 737,138

7 Claims. (Cl. 229—43)

1

The present invention relates to improvements in cartons.

An object of the present invention is to provide an improved carton having rigidity and which is efficient in stopping the seeping of material therefrom.

A further object is to provide a carton which, although made of relatively thin gauge material, has strength and good appearance.

A further object is to provide a blank for an improved carton in which wastage of material is minimized.

A further object is to provide a carton and a blank for forming said carton having the advantage that sealing of the carton may be accomplished without crushing, even though the carton contains only non-rigid material.

A further object is to provide an improved carton well adapted to meet the needs of commercial service.

Further objects will appear as the description proceeds.

Referring to the drawings:

Figure 1 is a view of a blank embodying the principles of the present invention; the blank being shown with that surface uppermost which is to be presented inwardly of the carton.

Figure 2 is a view in perspective of the blank illustrated in Figure 1, having the four side walls or panels thereof assembled in operative position, the top and bottom closures being open;

Figure 3 is a view similar to Figure 2, but with the bottom closure in closed position and showing the top closure at an intermediate stage of assembly;

Figure 4 is a perspective view illustrating the top closure in a later stage of assembly;

Figure 5 shows a completely sealed carton;

Figure 6 is a sectional view taken along the plane indicated by the arrows 6—6 of Figure 5; and

Figure 7 is a sectional view taken along the plane indicated by the arrows 7—7 of Figure 5.

Referring first to Figure 1, the numeral 10 indicates a blank which may be of cardboard or the like. The particular blank chosen for illustration is intended for a carton having uniform cross-section throughout its length, with the end closures disposed in right angular relationship with the side walls or panels, although the invention is equally applicable to cartons having tapering walls, that is, cartons of the nesting type.

The blank 10 chosen for illustration is generally rectangular in cross-section. Said blank

is provided with parallel side edges 12 and 13, and between said edges 12 and 13 are crease lines 14, 15, 16 and 17.

Figure 1 shows the surface of the blank 10 which will be presented inwardly of the carton and the crease lines 14, 15, 16 and 17 will be ruled into the blank from the upper surface whereby to bias upwardly the parts adjacent to said crease lines, that is, said crease lines bias said parts inwardly of the carton. Such crease lines are represented in Figure 1 by solid lines with dots spaced therealong. Lines ruled into the other side of the blank 10 are represented in Figure 1 by solid lines.

15 Crease line 14 is spaced from the crease line 15, and the crease line 16 is spaced from the crease line 17, a distance approximately equal to the width of the front or rear wall or panel of the carton.

20 Crease line 14 is spaced from the side edge 12, and the crease line 15 is spaced from the crease line 16, a distance approximately equal to the width of either of the two opposite narrow side walls or panels of the carton.

25 Spaced between the crease line 17 and the edge 13 is a connector section, which is utilized for securing the blank into a continuous outline, rectangular in cross-section.

The part of the blank 10 between the edge 30 12 and the crease line 14 provides the wall or panel 18, referred to hereinafter as the first wall or panel.

The part of the blank between the crease lines 14 and 15 provides the wall or panel 19, referred to hereinafter as the second wall or panel.

35 The part of the blank between the crease lines 15 and 16 provides the wall or panel 20, referred to hereinafter as the third wall or panel.

The part of the blank between the crease lines 16 and 17 provides the wall or panel 21, referred to hereinafter as the fourth wall or panel.

The part between the crease line 17 and the edge 13 is the connector section 22.

The top and bottom edges of the panel 18 (the first panel) are defined respectively by the crease lines 23 and 24; the top and bottom edges of the panel 19 (the second panel) are defined respectively by the crease lines 25 and 26; the top and bottom edges of the panel 20 (the third panel) are defined respectively by the crease lines 27 and 28; the top and bottom edges of the panel 21 (the fourth panel) are defined respectively by the crease lines 29 and 30; and the top and bottom edges of the connector section 22 are defined respectively by the crease lines 31 and 32.

3

For convenience in folding, crease line 25 at the top of the panel 19 will be of a slightly higher level than the crease line 29, which latter crease line will be of a slightly higher level than the crease lines 23 and 27, which may be in alignment with each other. The differences in level of the crease lines referred to will be approximately equal to the thickness of the material of the blank 10. The crease line 31 will be at a lower level than the crease lines 23 and 27 an amount approximately twice the thickness of the material of the blank 10.

Swingingly connected to the panel 18 (the first panel), along the crease line 23, is the tab 33, which tab is defined by the edge 34 in alignment with the crease line 23, the edge 35 offset inwardly from the edge 12, the edge 36, the edge 37 (which may be in alignment with the edge 12), the edge 38, the edge 39, the slit 40 and crease line 41. The crease line 41 is disposed in forty-five degree relationship with the crease line 23 and communicates with the juncture of crease lines 23 and 14. The intersection of crease line 41 and the slit 40 lies in the broken line 42a, which is in alignment with the edge 36.

Swingingly mounted at the top of the wall or panel 19 (the second panel) is the flap 43, defined by the crease line 25, the crease line 44, the edge 45, the edge 46, the edge 47, and the crease line 48. The edge 45 and crease line 44 will preferably be in alignment with each other, and the edge 47 and the crease line 48 will be in alignment with each other, the edge 45 and crease line 44 on the one side, and the edge 47 and the crease line 48 on the other side being offset inwardly from their respective crease lines 14 and 15. The edge 39 will preferably be offset slightly toward the left from alignment with the crease line 14.

Swingingly mounted at the top of the panel 20 (the third panel) is the tab 49, defined by the crease line 27, crease line 50, slit 51, edge 52, edge 53, edge 54, slit 55, and crease line 56. Said crease lines 50 and 56 are disposed in forty-five degree relationship with the crease line 27 and intersect said crease line 27 at the junctures thereof with the crease lines 15 and 16. The upper extremities of the crease line 56 and 56 terminate approximately at the broken line 42b, which also marks the slits 51 and 55. Broken lines 42a and 42b are in alignment with each other.

Swingingly mounted above the panel 21 (the fourth panel) is the flap 57, defined by the crease line 29, the crease line 58 (which extends up to approximately the broken line 42d), edge 59, edge 60, edge 61, edge 62, edge 63, edge 64, edge 65, and crease line 66 (which also extends up to approximately the broken line 42d). The edges 59 and 65 communicate with the edges 60 and 64, respectively, at the broken line 67, which is spaced from the edge 62 a distance approximately equal to or a little greater than the spacing of the broken line 42a from the crease line 23. The edge 61 is disposed in forty-five degree relationship with the edge 60 and the edge 62. The edge 63 is disposed in forty-five degree relationship with the edges 62 and 64.

Swingingly mounted at the top of the connector section 22 is the flap 68, defined by the crease line 31, crease line 69, slit 70, edge 71, edge 72, and edge 73. The crease line 69 communicates with the juncture of the crease lines 31 and 17. The crease line 66 and the edge 65 will preferably be in alignment with each other and will be offset slightly toward the left from the crease line 17. The slit 70 will be disposed above the

4

crease line 31 a distance approximately equal to or slightly less than the spacing between the crease lines 23 and 42a.

The dimension of the cut-out portion bounded by the lines 34, 35 and 36 in the direction parallel with the crease line 23 is sufficient to receive the web 77; that is, said dimension is equal to or slightly greater than the length of the slit 70 whereby the web 77 may be received within said cut-out portion, and tab 33 and flap 57 may be folded down into operative positions without interference.

The crease line 44, crease line 41 and slit 40 bound a web-corner 74 of unclosed approximately right angular triangular contour of which the crease line 41 is the hypotenuse. The crease line 48, crease line 50 and slit 51 bound a web-corner 75 of unclosed approximately right angular triangular contour of which the crease line 50 is the hypotenuse. The crease line 50, crease line 56 and slit 55 bound a web-corner 76 of unclosed approximately right angular triangular contour of which the crease line 56 is the hypotenuse. The crease line 66, slit 70 and crease line 69 bound a web-corner 77 of unclosed approximately right angular triangular contour of which the crease line 69 is the hypotenuse.

The crease lines 41, 50, 56 and 69, all represented by plain solid lines, will be ruled into the blank 10 from the under side thereof, that is, from the side which will be presented outwardly of the carton. The other crease lines, represented by solid lines with dots spaced therealong, are reversely ruled into the blank 10, that is, are ruled into the surface of the blank presented upwardly in Figure 1, that is, on the surface which is presented inwardly of the carton.

The part of the blank below the crease lines 24, 26, 28, 30 and 32 comprises the structure 40 forming the bottom closure of the carton. This bottom closure may take any preferred form. The particular structure illustrated is like that represented above the crease lines 23, 25, 27, 29 and 31. The descriptive matter applying to the 45 upper closure applies as well to the bottom closure as illustrated in Figure 1.

In forming the blank 10 into a carton, said blank will be formed into a tube of rectangular cross-section, the connector section 22 being laid 50 flatwise against the portion of the panel 18 (the first panel) adjacent to the edge 12. The flap 68 of the connector section will be laid flatwise against the edge portion of the tab 33. Said connector section 22 and said flap 68 will be adhesively secured to the panel 19 and tab 33, the parts 55 assuming the positions illustrated in Figure 2.

As indicated above, any preferred type of bottom closure may be used, although a bottom closure similar to the top closure is illustrated. In 60 any case the bottom closure will be folded into operative position as illustrated in Figure 3.

The tab 33 with the flap 68 secured thereto may then be folded down into right angular relationship with the panel 18. At the same time, the tab 49 will be folded down into right angular relationship with the panel 20, the parts assuming the positions as illustrated in Figure 3.

The flap 57 will then be folded down into flat- 70 wise engagement with the tabs 33 and 49 substantially as illustrated in Figure 4.

The web 77 will now lie in flatwise engagement with that portion of the flap 68 lying between the crease line 69 and the edge 73. This double 75 fold of material will be received within the cut-

out defined by the edges 34, 35 and 36 of the tab 33. The web 74 will be received within the triangular cut-out defined by the edges 63 and 64. The web 75 will be received within the triangular cut-out defined by the edges 60 and 61. The flap 43 will then be folded down into flatwise engagement with the flap 57.

The contacting surfaces of the various parts of the upper closure will be adhesively secured together and the parts will assume the positions illustrated in Figure 5.

By reason of the web-corners provided by the webs 74, 75, 76 and 77, and by reason of the cut-outs for receiving said web-corners, a sift-proof closure is provided, the sift proofness being promoted by reason of the fact that there is uniformity of thickness in the closure.

Although a preferred embodiment of the present invention has been described in detail, many modifications will occur to those skilled in the art. It is intended to cover all such modifications which fall within the scope of the appended claims.

What is claimed is:

1. A blank for a carton having crease lines dividing said blank into a first panel, a second panel, a third panel, a fourth panel and a connector section, said first panel and said third panel being provided with tabs swingingly united thereto at the tops thereof, said second panel and said fourth panel and said connector section being provided with flaps swingingly connected thereto at the tops thereof, said flap of said second panel being connected to said tabs through webs of unclosed approximately triangular contour, said flap of said fourth panel being connected to the tab adjacent thereto and to the flap of said connector section through webs of unclosed approximately triangular contour, said tab of said first panel and said flap of said fourth panel being provided with cut-out portions to receive said webs whereby said tabs and said flaps may be folded down into closing position and provide a closure of substantially uniform thickness.

2. A blank for a carton having crease lines dividing said blank into a first panel, a second panel, a third panel, a fourth panel, and a connector section, said first panel and said third panel being provided with tabs swingingly united thereto at the tops thereof, said second panel and said fourth panel and said connector section being provided with flaps swingingly connected thereto at the tops thereof, said flap of said second panel being connected to said tabs through webs of unclosed approximately triangular contour, said flap of said fourth panel being connected to the tab adjacent thereto and to the flap of said connector section through webs of unclosed approximately triangular contour, each of said webs being bounded by two crease lines and a slit said tab of said first panel and said flap of said fourth panel being provided with cut-out portions to receive said webs whereby said tabs and said flaps may be folded down into closing position and provide a closure of substantially uniform thickness.

3. A blank for a carton having crease lines dividing said blank into a first panel, a second panel, a third panel, a fourth panel, and a connector section, said first panel and said third panel being provided with tabs swingingly united thereto at the tops thereof, said second panel and said fourth panel and said connector section being provided with flaps swingingly connected thereto at the tops thereof, said flap of said sec-

ond panel being connected to said tabs through webs of unclosed approximately triangular contour, said flap of said fourth panel being connected to the tab adjacent thereto and to the flap of said connector section through webs of unclosed approximately triangular contour, each of said webs being bounded by two crease lines and a slit, the crease lines bounding each of said webs being mutually reversed to bias the material joined by said crease lines in opposite directions said tab of said first panel and said flap of said fourth panel being provided with cut-out portions to receive said webs whereby said tabs and said flaps may be folded down into closing position and provide a closure of substantially uniform thickness.

4. A carton having a first panel, a second panel, a third panel, a fourth panel and a connector section, said connector section being adhesively secured to said first panel, said first and third panels having tabs swingingly united thereto at the tops thereof, said second panel, said fourth panel and said connector section having flaps swingingly connected thereto at the tops thereof, said flap of said connector section being adhesively secured to the inside of the tab of said first panel, said flap of said second panel being connected to said tab of said first panel, said tab of said third panel being connected to said flaps of said second and fourth panels and said flaps of said connector section being connected to said flap of said fourth panel through webs, said tab of said first panel and said flap of said fourth panel being provided with cut-out portions to receive said webs whereby said tabs and said flaps may be folded down into closing position and provide a closure of substantially uniform thickness.

5. A carton having a first panel, a second panel, a third panel, a fourth panel and a connector section, said connector section being adhesively secured to said first panel, said first and third panels having tabs swingingly united thereto at the tops thereof, said second panel, said fourth panel and said connector section having flaps swingingly connected thereto at the tops thereof, said flap of said connector section being adhesively secured to the inside of the tab of said first panel, said flap of said second panel being connected to said tab of said first panel, said tab of said third panel being connected to said flaps of said second and fourth panels and said flap of said connector section being connected to said flap of said fourth panel through webs, said tab of said first panel and said flap of said fourth panel being provided with cut-out portions to receive said webs whereby said tabs and said flaps may be folded down into closing position and provide a closure of substantially uniform thickness, each of said webs being bounded by two crease lines and a slit.

6. A carton having a first panel, a second panel, a third panel, a fourth panel and a connector section, said connector section being adhesively secured at said first panel, said first and third panels having tabs swingingly united thereto at the tops thereof, said second panel, said fourth panel and said connector section having flaps swingingly connected thereto at the tops thereof, said flap of said connector section being adhesively secured to the inside of the tab of said first panel, said flap of said second panel being connected to said tab of said first panel, said tab of said third panel being connected to said flaps of said second and fourth panels and said flap of

10 said connector section being connected to said flap of said fourth panel through webs, said tab of first panel and said flap of said fourth panel being provided with cut-out portions to receive said webs whereby said tabs and said flaps may be folded down into closing position and provide a closure of substantially uniform thickness, the crease lines bounding each of said webs being mutually reversed to bias the material joined by said crease lines in opposite directions.

15 7. A carton having a first panel, a second panel, a third panel, a fourth panel and a connector section, said connector section being adhesively secured to said first panel, said first and third panels having tabs swingingly united thereto at the tops thereof, said second panel, said fourth panel and said connector section having flaps swingingly connected thereto at the tops thereof, said flap of said connector section being adhesively secured to the inside of the tab of said first panel, said flap of said second panel being connected to said tab of said first panel, said tab of said third panel being connected to said flaps of said second and fourth panels and said flap of said connector section being connected to said flap of said fourth panel through webs, said tab of said first panel and said flap of said fourth

20 panel being provided with cut-out portions to receive said webs whereby said tabs and said flaps may be folded down into closing position and provide a closure of substantially uniform thickness, each of said webs being bounded by two crease lines and a slit, one only of the crease lines of each of said webs communicating with the junction of the top and side edges of its adjacent panel.
